UNITED STATES PATENT OFFICE.

MELCHIOR J. C. WALTER, OF LYNN, MASSACHUSETTS, AND JOSEF MAIER, OF NEWARK, NEW JERSEY.

LEATHER-SPLITTING MACHINE.

1,264,232.

Specification of Letters Patent. Patented Apr. 30, 1918.

Application filed November 14, 1917. Serial No. 202,027.

To all whom it may concern:

Be it known that we, MELCHIOR J. C. WALTER, a citizen of the United States, and resident of Lynn, county of Essex, and State of Massachusetts, and JOSEF MAIER, a subject of the Emperor of Germany, and resident of Newark, county of Essex, and State of New Jersey, have invented certain new and useful Improvements in Leather-Splitting Machines, of which the following is a specification.

This invention relates to improvements in leather splitting machines of the belt-knife type and has for its objects the provision of simple means for quickly and accurately adjusting the gage and pressure rolls relatively to each other and relatively to the path of the knife, and to provide simple means for adjusting the feed table in unison with the gage roller to adapt the rolls to feed leather of different thicknesses to the knife and to adapt the machine to split leather into sheets of various thicknesses.

In the drawings, Figure 1 is a vertical longitudinal sectional view on the line I—I of Fig. 2;

Fig. 2 a plan view of the machine;

Fig. 3 an end elevation showing the right-hand end of the machine;

Fig. 4 an end elevation of the left-hand end of the machine;

Fig. 5 a vertical sectional view on the line V—V of Fig. 1;

Fig. 6 a horizontal sectional view on the line VI—VI of Fig. 1;

Fig. 7 a plan view showing one of the supporting saddles for the lower feed and gage roller;

Fig. 8 a vertical central transverse section of the parts shown in Fig. 7;

Fig. 9 a vertical sectional view on the line IX—IX of Fig. 10; and

Fig. 10 a fragmentary vertical transverse sectional view showing parts of the supporting and guiding means for the lower feed and gage roller.

Referring to the various parts by numerals, the machine is provided with a suitable bed 1, supported on standards or upright frame members 2, and side frame members or uprights 3 and 4 extending upwardly from the bed 1 and held thereto by suitable bolts, or in any other desired manner. A

vertically adjustable feed table 5 is supported between the side members 3 and 4 of the frame at the forward side of the machine, and a belt-knife guide or cutter-bar 6 is supported between said side members at the rear of the machine. A pair of belt-knife driving pulleys or drums 7 and 8 are fixed on shafts 9 and 10 journaled in suitable bearings at opposite ends of the machine, and a belt-knife 11 passes over said pulleys or drums and passes through the usual guide slot 12 in the cutter-bar or knife-guide 6. The shaft 9 is driven from the main driving shaft 13 through bevel gears 14 and 15, and the main driving shaft 13 is driven from any suitable source of power, not shown. The parts heretofore described are of well-known construction.

To adapt the machine to split sheets or strips of various thicknesses from a hide or sheet of leather, we provide an adjustable gage and feed roller 16 supported below and adjacent to the forward or cutting edge of the belt-knife 11 on a shaft 17. The shaft 17 is journaled at its ends in substantially rectangular bearing blocks 18 adapted to slide vertically in openings or guide-ways 19 formed in the side members 3 and 4 of the main frame of the machine. The bearing blocks 18 are connected by posts 20 with the ends of an adjusting bar 21, extending longitudinally of the machine and guided at its ends in openings or ways 22 formed in the side members 3 and 4 of the frame below the guide-ways 19. The posts 20 are formed with reduced portions at each end thereof, fitting in sockets 23 and 24 formed respectively in the bearing blocks 18 and the ends of bar 21. The shoulders formed by the reduced ends of posts 20 prevent movement of blocks 18 and bar 21 toward each other, and said parts are held against movement away from each other by yokes 25 embracing the blocks 18 and held to bar 21 by suitable bolts 26. Posts 20 extend through and are slidably guided in apertures 27 in the portions of the side frame members 3 and 4 extending between the guide-ways 19 and 22.

The bar 21 is adapted to be adjusted vertically by means of a pair of posts or threaded rods 28 held to the bar 21 at their upper ends by pins 29 extending through the

bar and posts. Each threaded post 25 has threaded thereon a worm wheel 27 meshing with worms 28 keyed on a shaft 29 by keys 30 which are removably held in place by suitable set screws 31. The shaft 29 is adapted to be manually rotated in either direction, to shift the bar 21 and gage roller 16 toward and from the path of the belt-knife 11, by means of a thumb-wheel 32 fixed on the upper end of a shaft 33 journaled in bearings 34 and 35 held to the side frame member 3. A bevel pinion 36 is fixed on the lower end of shaft 33 and meshes with a bevel gear 37 fixed on shaft 29.

15 It will be obvious that the bearing blocks 18 supporting gage roller 16 may be simultaneously adjusted through the connections just described. It is sometimes desirable to adjust one of the blocks 18 without shifting the other block, and it will be obvious that by loosening one of the set screws 31 and removing the key 30 held thereby, the operative connection between shaft 29 and either threaded post 25 will be broken, thus 20 permitting the adjustment of one end of bar 21 and roller 16 by thumb wheel 32 without shifting the other end of the bar 21 and roller 16. The hub 27 of each worm wheel 27 has a bearing at its upper 25 end in an aperture in a plate 71, and a bearing at its lower end in the enlarged upper portion of an aperture 72 in the bed 1 through which the lower end of post 25 extends. The plates 71 are held to the bed 30 1 by screws 73 threaded in bosses 74 formed on the upper surface of the bed. The plates 71 serve to prevent movement of the worm wheels 27 longitudinally of the threaded posts 25 and also serve, in conjunction with 35 the bearings in the upper ends of apertures 72, to maintain the worm wheels 27 in mesh with worms 28 on shaft 29.

40 The feed table 5 is supported on the upper ends of three substantially triangular brackets 78, being held thereto by suitable screws or other fastening devices 79, and said brackets 78 are held at their lower ends to the adjusting bar 21 by screws 80 or other suitable means. It will thus be seen that the 45 table 5 and roll 16 are adjustable vertically relatively to the path of the belt-knife in unison.

To adapt the machine to operate on hides or sheets of leather of various thicknesses, we 50 provide an adjustable feed or pressure roller 38 supported above the path of the belt-knife 11 and coöperating with the feed and gage roller 16 to feed the leather to the belt-knife. The roller 38 is mounted on a shaft 55 55 39 journaled at its ends in bearings 40 formed at the rear ends of a pair of arms 41 pivotally held intermediate their ends to the side members 3 and 4 of the frame by pivot screws or bolts 42 and 43. The bearings 40 extend outwardly through openings

or cut-away portions in the side members 3 and 4 of the frame.

55 Shaft 39 is adapted to be rotated by pinions 44, 45 and 46, through a suitable gear train driven from the main driving shaft 13, and the shaft 17 is adapted to be driven in the opposite direction from the same gear train, through pinions 47 and 48. The gear train may comprise a pinion 49 fixed on shaft 13 and meshing with a pinion 50, 75 a pinion 51 fixed on the same shaft as pinion 50 and meshing with a pinion 52, and a pinion 53 fixed on the same shaft as pinion 52 and meshing with pinion 44 and also meshing with pinion 47. The arrangement 80 of the pinions 45 and 47 with respect to the pinions 46 and 48, respectively, is such that the shafts 17 and 39 may be adjusted vertically without interrupting the driving connections.

85 Both of the arms 41 are adapted to be rocked about their pivots 42 and 43 simultaneously to shift the pressure roller 38 toward and from the gage roller 16. For this purpose, we provide a rock-shaft 54 journaled at its ends in bearing blocks 55 held to the forward edges of the frame members 3 and 4. A pair of eccentrics 56 are fixed on the rock-shaft 54 and engage in eccentric straps 57 held to the lower ends of a pair 90 of rods 58. The upper ends of rods 58 pass through elongated apertures 59 in the forward ends of the pivoted arms 41. The lower sides of the levers 41 bear upon stop nuts 60 threaded on the rods 58 and are held 95 thereagainst by stiff coil springs 61 interposed between the upper sides of the arms 41 and stop nuts 62 threaded on the upper ends of rods 58. Suitable washers may be mounted on rods 58 at each side of the 100 forward ends of arms 41, if desired, and any other suitable rocking or pivoted connection may be provided between rods 58 and arms 41. The shaft 54 is adapted to 105 be rocked by a hand-lever 63 fixed thereto, and said lever 63 may be locked in its adjusted position by a thumb-screw 64 extending through the lever and an arcuate slot in a curved arm 65 which is held to the bed 1 at its lower end in any suitable manner. The worm gearing for adjusting bar 21 is self-locking and will hold the bar 21 110 in its adjusted position.

115 The gage roller 16 is supported intermediate its ends by a pair of saddles 66 in each of which is journaled a pair of spaced anti-friction supporting rollers 67 engaging the under side of roller 16. The saddles 66 are supported on the adjusting bar 21, to move therewith, by means of depending 120 threaded stems or posts 68 extending through apertures in the bar 21. The saddles are locked in their adjusted position by lock nuts 69 and 70 threaded on the 125 posts 68 respectively above and below the 130

bar 21. The saddles and rollers 66 and 67 prevent sagging of the gage roller 16 and are adjustable therewith.

What we claim is:

- 5 1. In a leather-splitting machine of the belt-knife type, the combination with the gage roll of a vertically adjustable bar, means carried by said bar adjacent its ends for rotatably supporting the gage roll below 70
10 the path of the cutting edge of the belt-knife, and anti-friction thrust-resisting means supported on said bar and engaging under the gage roll intermediate the ends of the roll.
- 15 2. In a leather splitting machine of the belt-knife type, the combination with the belt-knife, of a gage roll, a vertically adjustable bar, means carried by said bar for rotatably supporting the gage roll at its 75
20 ends below the path of the cutting edge of the knife, and means for simultaneously or independently shifting the ends of said bar vertically.
3. In a leather splitting machine of the belt-knife type, the combination with the belt-knife, of a gage roll, a vertically adjustable bar, means carried by said bar for rotatably supporting the gage roll at its ends below the path of the cutting edge of the 80
25 knife, anti-friction thrust-resisting means carried by said bar and engaging beneath the gage roll intermediate its ends, a pressure roll rotatably supported above the path of the cutting edge of the knife, and means 85
30 for adjusting said pressure roll toward and from the gage roll.
4. In a leather splitting machine, the combination of a belt-knife, means for driving said knife, a pair of opposed coöperating 90
40 rollers disposed at opposite sides of the path of the knife, means for rotating said rollers in opposite directions from the same source of power to feed a sheet of leather to the knife, pivoted supporting means for 95
45 the ends of one of said rollers, means for simultaneously rocking said pivoted supporting means to adjust the roller supported thereby relatively to the other roller, reciprocable supporting bearings for the other of 100
50 said rollers, and means for simultaneously reciprocating said supporting bearings to adjust the roller supported thereby relatively to the path of the knife.
5. In a leather splitting machine, the combination of a belt-knife, means for driving said knife, a pressure roller rotatably supported above the path of the knife, a co-operating roller below the path of the knife, a vertically adjustable bar, bearings carried 105
55 by said bar for rotatably supporting the ends of the lower roller, saddles carried by said bar, and rollers mounted in said saddles and adapted to engage and support said lower roller intermediate its ends.
6. In a leather splitting machine of the 110
60
- 65 belt-knife type, the combination with the knife and pressure means, of a gage roller, a reciprocable bar, bearings carried by said bar for rotatably supporting said gage roller, means for guiding said bar, threaded rods held to the bar, a shaft journaled parallel with said bar, worms mounted on said shaft, worm-wheels threaded on said rods and meshing with the worms on said shaft, means for holding said worm-wheels against movement longitudinally of said rods, and means for rotating said shaft in either direction to reciprocate said bar.
7. In a leather splitting machine, the combination of a splitting knife, a pair of opposed feed rolls, means for rotatably supporting the lower roll at each end thereof below the plane of the cutting edge of the knife, means for simultaneously adjusting both ends of said supporting means vertically, a feed table mounted on said roll supporting means and adjustable therewith, and means for independently adjusting the upper roll.
8. In a leather-splitting machine of the belt-knife type, the combination of a pair of opposed feed rolls supported adjacent the cutting edge of the knife at opposite sides of the path thereof, a feed table, means for vertically adjusting the feed table in unison with one of said rolls, means for independently adjusting the other of said rolls, and constantly maintained driving connections between said rolls and a common source of power.
9. In a leather splitting machine, the combination of a knife, a gage roll, a vertically adjustable bar, means carried by said bar adjacent the opposite ends thereof for rotatably supporting the gage roll at its ends, means for simultaneously adjusting both ends of said bar vertically, brackets rigidly held to said bar, and a feed table held to said brackets and adjustable in unison with the gage roll.
10. In a leather splitting machine of the belt-knife type, the combination with the belt-knife of a gage roll, a vertically adjustable support for the gage roll, a feed table held to said adjustable gage roll support, and means for simultaneously or independently shifting the ends of said support vertically.
11. In a leather splitting machine, the combination of a splitting knife, a gage roll, a reciprocable support for the gage roll, threaded rods rigidly held to said support, a shaft, worms mounted on said shaft, worm wheels threaded on said rods and meshing with the worms on said shaft, means for holding the worm wheels against movement longitudinally of said rods, and means for rotating said shaft in either direction.
12. In a leather splitting machine, the combination of a splitting knife, a gage roll, a 130
120

reciprocable support for the gage roll, threaded rods rigidly held to said support, a shaft, worms mounted on said shaft, worm wheels threaded on said rods and meshing 5 with the worms on said shaft, means for holding the worm wheels against movement longitudinally of said rods, means for rotating said shaft in either direction, and means whereby either of said threaded rods may 10 be adjusted independently through its co-operating worm and worm wheel and said shaft.

13. In a leather-splitting machine, the combination of a splitting knife, pressure 15 means, a gage roll coöperating with the pressure means, an adjustable support for the gage roll, thrust-resisting means carried by said support and engaging the gage roll in-

termediate its ends, and bearings carried by said support for rotatably supporting the 20 ends of the gage roll.

14. In a leather-splitting machine, the combination of a splitting knife, pressure means, a gage roll coöperating with the pressure means, an adjustable support, bearings 25 carried by said support for rotatably supporting the gage roll at its ends, anti-friction thrust-receiving means engaging said roll, and means carried by said support for adjusting the thrust-receiving means relatively to the gage roll.

In testimony whereof we hereunto affix our signatures this 10th day of November, 1917.

MELCHIOR J. C. WALTER.
JOSEF MAIER.
